AND MANUFACTURING COMPANY, A CORPORATION OF PENNSYLVANIA.

SYSTEM OF DISTRIBUTION.

1,082,561.

Specification of Letters Patent.

Patented Dec. 30, 1913.

Application filed December 21, 1910. Serial No. 598,523.

To all whom it may concern:

Be it known that I, ELMER H. SCHWARZ, a citizen of the United States, and a resident of New York city, in the county of 5 New York and State of New York, have invented a new and useful Improvement in Systems of Distribution, of which the following is a specification.

My invention relates to systems of electrical distribution and particularly to constant alternating current lighting systems.

The object of my invention is to provide a polyphase constant alternating current distribution or lighting system which shall 15 have a low initial cost for installation and in which the electrical losses due to resistance shall be less than in other systems heretofore employed. These advantages are attained by connecting the lamps or other 20 translating devices in series relation in each of the three phases of the system and in connecting the phases together at a point beyond the translating devices, thus eliminating the necessity for employing return conductors.

Heretofore in systems in which translating devices, such as arc lamps, have been in series relation, it has been customary to place the lamps in separate single-phase circuits having no interconnection and distinct from each other so that return conductors have been necessary for each circuit. The present system is distinguished from such old systems in the manner set forth.

Figure 1 of the accompanying drawings is a diagrammatic view of a system embodying one form of my invention, and Figs. 2, 3 and 4 are similar views of modifications of the system of Fig. 1.

In the system of Fig. 1, the primary coils 1, 2 and 3 of a three-phase constant-current regulating device are connected, in any desired relation to each other, to a three-phase supply circuit 4—5—6, the core 7 of said 45 device comprising three vertical legs that are joined by a yoke and are respectively surrounded by the said coils. As here shown, the primary coils of the regulator are independently movable with respect to each other, and also with respect to secondary coils 8, 9 and 10, though, if desired, the secondary coils may be made independently movable while the primary coils are retained in a stationary position. The movable coils

are independently counterbalanced by convenient means such as weights, as shown in the drawing. The terminals of the secondary coils 8, 9 and 10 are respectively connected to distributing circuit conductors 11, 12 and 13 corresponding to the different phases of the system, and the remaining terminals of the secondary coils are connected together. Lamps 14, or other translating devices of any suitable character, are connected in series relation in the circuits of each of the conductors 11, 12 and 13, and the said conductors are connected together at points beyond the translating devices. The connected terminals of the coils 8, 9 and 10 and the remote ends of the conductors 11, 12 and 13 are shown connected to the ground, though such grounded connections may be omitted, if desired.

Since the several phase conductors of the distributing circuit are connected together at their ends remote from the constant current regulator and beyond the translating devices, no return conductors in addition to those illustrated are necessary, and, consequently, there is a great saving of the material composing the conductors over what would be necessary if the several phases of the system were independent and unconnected. Also, the electrical losses in the system which are due to resistance are, accordingly, materially less than in systems in which the phases are entirely separate. If one phase of the present system becomes disabled, the remaining phases will still continue to operate and the regulator will maintain constant currents therein, since the movable coils thereof are independently movable. For this reason, also, the current in each phase is independently regulated and is maintained constant, irrespective of the conditions affecting the other phases.

The present system may be employed with advantage under several different kinds of practical conditions. For instance, consider the street lighting of a comparatively small community requiring only about as many lamps as are ordinarily placed in one single phase circuit. By using the present system, the phases of the supplying generator may be kept in balance, only one-third of the total number of lamps are rendered useless in case one phase of the circuit is disabled, and, if the neutral points are grounded, the

voltage strain is only one-third of that in a single phase system, while the maximum voltage between any two conductors of the system is $\frac{1}{\sqrt{3}}$ or about $\frac{1}{3}$ of that in a single phase system.

In systems having more than enough lamps for one single phase circuit, a material saving in the cost of conductors and in resistance losses may be effected by the use of the present system, particularly when the community to be lighted is at some distance from the generating or sub-station.

In Fig. 2, a reactance type of regulator is employed instead of the transformer type shown in Fig. 1, but, in other respects, the character of the system and its mode of operation are the same. In this system, the neutral point of the generator or intermediate potential transformers supplying the system may be grounded.

In some cases, it may be desirable to employ a plurality of single phase constant-current regulating devices, particularly when only one lamp circuit is installed at a time, which may occur in a growing community. A system in which a separate constant-current regulating device of the transformer type is employed in each phase is shown in Fig. 3, and, in Fig. 4, is shown a similar system in which the regulating device is of the reactance type. In these systems also, the circuits are grounded, in order to reduce the potential strains to values corresponding to those found in a single phase system. In each of these systems, the lamp circuits are grounded at their remote or connected ends, and, in Fig. 3, the connected terminals of the secondary windings of the regulating transformers are also grounded. In Fig. 4, the neutral point of the generator or intermediate potential transformers supplying the system is grounded. The grounded connections may, of course, be omitted, if desired.

I claim as my invention:

1. A system of distribution comprising a three-phase distribution circuit and a plurality of translating devices connected in series relation in each of the phases, and independently operative constant-current regulating means for each of the phases.

2. In a system of distribution, the combination with a polyphase constant-current regulator having independently movable coils for its respective phases, of a polyphase distributing circuit leading from the regulator, and series-connected translating devices in each of the phases of the distributing circuit, the conductors of the several phases of the said circuit being connected together at a point beyond the translating devices.

3. In a system of distribution, the combination with a three-phase constant-current regulator having independently movable coils for its respective phases, of a three-phase distributing circuit leading from the regulator, and series-connected translating devices in each of the phases of the distributing circuit, the conductors of the several phases of the said circuit being connected together at a point beyond the translating devices, and the neutral points of or connections between the said phases being grounded.

4. In a system of distribution, the combination with a three-phase constant-current regulator having independently movable coils for its respective phases, of a three-phase distributing circuit leading from the regulator, and series-connected translating devices in each of the phases of the distributing circuit, the conductors of the several phases of the said circuit being connected together at a point beyond the translating devices.

5. A system of distribution comprising a polyphase distributing circuit, series-connected translating devices in each of the phases of the distributing circuit, the conductors of the several phases of the said circuit being connected together at a point beyond the translating devices, and independently operative constant current regulating means for each of the phases of the distributing circuit.

Signed at New York, in the county of New York and State of New York this ninth day of December A. D. 1910.

ELMER H. SCHWARZ.
